ELECTRICALLY OPERATED REGISTER

Louis Jean Joseph Schreiber, Paris, France, assignor to Western Electric Company, Incorporated, New York, N. Y., a corporation of New York

Application July 27, 1931, Serial No. 553,337
In Great Britain October 27, 1930

3 Claims. (Cl. 74—142)

This invention relates to electromagnetic counting mechanisms and more particularly to the stepping mechanisms therefor.

The object of this invention is to provide a more positive, accurate, efficient and durable counting mechanism.

According to this invention the actuating mechanism of an electromagnetically operated register device comprises an armature, a ratchet wheel, a pawl for advancing said wheel in response to the movement of said armature and a pawl for preventing the advance of said wheel more than one step at a time, a single controlling spring for said armature and pawls, and a retaining pawl for preventing the backward movement of said wheel.

In the preferred embodiment, the single controlling spring is anchored to an adjustable member located immediately to the rear of the counting wheels so that the spring adjustment can be varied from the front of the register. In a number of other arrangements the armature spring is located immediately above the armature in the space provided due to the thickness of the connecting lug pile-up or terminal block; but in my preferred embodiment this space can be used for contact springs actuated by the movement of the armature.

One embodiment of the invention for use in telephone or like systems will now be described with reference to the accompanying drawing in which:

Fig. 1 shows a plan view of the magnetic core, armature, contact springs, stepping mechanism and terminal lugs of such a register;

Fig. 2 shows a side view of the structure shown in Fig. 1;

Fig. 3 shows diagrammatically the method of controlling the armature and pawl; and

Fig. 4 shows the pawl arrangement in perspective.

The coil of the electromagnet, the counting wheels, and the casing for enclosing the register are not shown in the drawing since they form no part of the invention. The patent to C. E. Scribner et al., No. 765,255, July 19, 1904, shows a service meter for telephone exchanges including the coil of the electromagnet, the counting wheels and the casing for enclosing the register.

Referring to Figs. 1 and 2, the core 18 of the electromagnet is mounted on a frame member 14 on which is also mounted the connecting lug pile-up or terminal block 20. Fixed between the member 14 and the pile-up is a thin plate spring 15 which has extensions on either side fastened

to the armature 16. At the end nearest the pile-up the armature is cut away at its sides so that the spring extensions are free for some little distance as shown in Fig. 1. The spring 15 acts as a pivotal mounting for the armature and is so arranged that the armature is normally slightly spaced from the lower end of the member 14 (see Fig. 2). At its free end the armature has a turned down portion 17 adapted to cooperate with the pole piece of the core 18. On this end of the armature is fixed a non-magnetic arm 2. The free end of this arm is for the greater portion of its width curled over to form a bearing 3 for a pivot pin 18 which at its extremities forms a pivot for a member 4 which carries the pawl 5 at one end. For the remainder of its width (see Fig. 4) the member 2 carries an extension 1 formed as a stop pawl. At the end remote from the pawl 5 the member 4 carries an adjustable arm 6, between which and a member 8 fixed to the meter casing is mounted a spring 7. The pawls 5 and 1 form an escapement mechanism for a square toothed ratchet wheel 13 fixed to a counting wheel 12 forming part of the usual train of counting wheels. The member 9 fixed to the casing carries a spring 11 forming a retaining pawl for the toothed wheel 13.

It will be noted that the point of connection of the spring 7 to the member 6 is offset somewhat from the pivot axis of the pawl 5 so that the spring tends to maintain the pawl in contact with the wheel. At the same time the spring 7 acts as a return spring for the armature. The controlling force of the spring on pawl 5 can be adjusted by bending the member 8 toward or away from the pivotal axis of the pawl while the controlling action of the spring on the armature can be adjusted by bending the member 8 (see Fig. 2) to the right or to the left, the member 8 being fixed to the casing of the meter. The member 9 forms the back stop for the armature and is also adjustable. Between the insulating plates of the terminal block 20 are mounted the connecting lugs 21 for the magnet winding and for the contact springs 19 which are adapted to be operated by an insulating button 22 on the armature. It will be seen that these springs are positioned above the armature in the space necessitated by the height of the terminal block 20 and do not add to the size of the register.

When in normal position the spring 7 holds the pawls 1 and 5 in engagement with teeth of the ratchet wheel 13. Upon energization of the magnet, not shown, the armature 16 is attracted against the tension of spring 7 so that the turned

down portion 17 overlaps the lower end of the core 18. The pawl 1 is thus moved out of contact with the ratchet wheel 13 and the pawl 5 is drawn toward the right, as shown in Fig. 2, to engage the next tooth of the ratchet wheel. When the magnet becomes deenergized, spring 7 pulls the armature 16 back into normal position at the same time causing pawl 5 to rotate the ratchet wheel one step in a counter-clockwise direction as shown in Fig. 2. The pawl 1 reengages the next tooth of the ratchet wheel 13 after the previously engaged tooth has been advanced beyond its reach, thereby limiting the movement of the ratchet wheel to one step for each operation of the magnet.

What is claimed is:

1. In an electromagnetic counting mechanism, an armature, a ratchet wheel, a non-magnetic arm, one end of said arm fixed to the free end 20 of said armature, the other end of said arm being curled over for a portion of its width to form a bearing and further extended for the remainder of its width to engage said ratchet wheel as a stop pawl to limit the advance of said wheel to one step at a time, a pivot pin within said bearing, a driving pawl for advancing said wheel, said driving pawl being pivoted on said pin, the free end of said driving pawl engaging said ratchet wheel, and a single spring for controlling said armature and pawls.
2. In an electromagnetic counting mechanism,

an armature, a ratchet wheel, a non-magnetic arm, one end of said arm fixed to the free end of said armature, the other end of said arm being curled over for a portion of its width to form a bearing and further extended for the remainder of its width to engage said ratchet wheel as a stop pawl to limit the advance of said wheel to one step at a time, a pivot pin within said bearing, a driving pawl for advancing said wheel, said driving pawl being pivoted on said pin, the 10 free end of said driving pawl engaging said ratchet wheel, and a single spring for controlling said armature and pawls, said spring being attached to said driving pawl, the point of attachment being offset from the axis of rotation of 15 said driving pawl so that said spring tends to maintain said pawl in contact with said wheel.

3. In an electromagnetic counting mechanism, an armature, a ratchet wheel, a non-magnetic arm, one end of said arm fixed to the free end 20 of said armature, the other end of said arm being curled over for a portion of its width to form a bearing and further extended for the remainder of its width to engage said ratchet wheel as a stop pawl, a pivot pin within said bearing, a driving 25 pawl pivoted on said pin and engaging said wheel, and a single spring for controlling said armature and pawls, said pawls and spring forming an escapement mechanism to advance said ratchet wheel one step at a time.

LOUIS JEAN JOSEPH SCHREIBER.
